(57) CLAIM

The ornamental design for a combined video disk player and hard disk recorder, as shown and described.

DESCRIPTION

FIG. 1 is a perspective view of top, front and right side of a combined video disk player and hard disk recorder according to a first embodiment showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the top, front and right side of a combined video disk player and hard disk recorder according to a second embodiment;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view of the top, front and right side of a disk player according to a third embodiment;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof; and,

FIG. 21 is a bottom plan view thereof.

The elements shown in broken lines which are visible through transparent surfaces form no part of the claimed design. The lines shown on the surfaces in FIGS. 15, 16 and 21 are simulative of woodgrain and do not represent a particular pattern.
